United States Patent Office

Des. 189,421
Patented Dec. 13, 1960

189,421

ETAGERE

John J. Lubberts and Lambert J. Mulder, Grand Rapids,
Mich., assignors to Tomlinson of High Point, High
Point, N.C., a corporation of North Carolina

Filed Sept. 21, 1959, Ser. No. 57,633

Term of patent 14 years

(Cl. D33—19)

The figure is a front perspective view of an etagere embodying our new design.

The opposite side of the etagere is like the side shown, and the back of the base is substantially plain.

We claim:

The ornamental design for an etagere, substantially as shown and described.
